CHARLES P. KLEEBAUER, OF BROOKLYN, NEW YORK, ASSIGNOR TO COHOES ENVELOPE CO., INC., OF COHOES, NEW YORK, A CORPORATION OF NEW YORK.

TAG-ENVELOP.

1,291,023.

Specification of Letters Patent.

Patented Jan. 14, 1919.

Application filed March 14, 1917. Serial No. 154,687.

To all whom it may concern:

Be it known that I, CHARLES P. KLEEBAUER, a citizen of the United States, and a resident of the city of New York, borough 5 of Brooklyn, in the county of Kings and State of New York, have invented a new and Improved Tag-Envelop, of which the following is a full, clear, and exact description.

Among the principal objects which the 10 present invention has in view are: to enable an envelop of the character mentioned to be opened in transit for examination and re-closed to prevent the loss of the contents; to strengthen the structure of the envelop to 15 prevent the destruction of the same; and to reduce the cost of manufacture of envelops of the character mentioned.

Drawings.

20 Figure 1 is a rear view of an envelop constructed and arranged in accordance with the present invention, the envelop being shown in its open condition;

25 Fig. 2 is a detail view on an enlarged scale showing an end fragment of the envelop in service position, the flap being closed;

30 Fig. 3 is a rear view of an envelop having a modified form of construction to provide an extra securing means for said envelop;

Fig. 4 is an enlarged section showing a fragment of the upper end of the envelop, the closure flap being shown in service position;

35 Fig. 5 is a section on an enlarged scale, the section being taken as on the line 5—5 in Fig. 3;

Fig. 6 is a section showing an open end fragment of the envelop as in service relation, the flap of said envelop being shown 40 as torn away from its original fastening to permit access to the contents of the envelop for examination purposes;

Fig. 7 is a similar view showing the flap 45 as being tucked under the adjacent edge of the body after the envelop has been opened for examination of contents.

Description.

50 As seen in the drawings, a reinforcing patch 15 is adhered to the envelop closure flap 16 and envelop body portion 17, said body extending across the bending line 18 of the said flap. A short patch 19 is adhered to the envelop back portion 20 adjacent the

cut edge 21 thereof. Attention is drawn to the fact that the cut edges 21 and 22 of the flap 20 and flap 16, respectively, are complementary in shape, that is, the edge of each flap of each envelop is complementary to the 60 edge of the back of the envelop next successively separated from the web from which envelop blanks are formed. Therefore it is obvious that the patches 15 and 19 have complementary relation each to the other. 6:

During the course of manufacture of the envelop and after the patches 15 and 19 have been adhered to the blank, the perforations 23, 24 and 25 are punched, said perforations extending through said patches and the superposed envelop material. These perforations are so arranged that when the flap 16 is overturned on the body of the envelop, the three perforations aline as shown best in Fig. 4 of the drawings. When envelops constructed as above described are closed, a tie string of any suitable form may be extended through the alined perforations 23, 24 and 25 and in this position the envelop may be temporarily locked. 75 80

In the modified form shown in Fig. 2 of the drawings, provision is made for attaching the envelop to a package. These envelops are mostly intended for bills of lading or instructions or directions, to gain access to which it is found convenient to loosen the flap after the same has been closed and started from its original point of departure. To this end, a partially separated tag 26 is provided, said tag incorporating the perforation 23 by being partially separated from the flap 16 by a number of closely associated perforations 27. 85 90

In service, a tack 28 or other suitable fastening device is driven through the perforations 23, 24 and 25 and into the article to which the envelop is attached, the head of the tack extending over the side edges of the tag 26. 95

When, now, an envelop so constructed reaches the station where it is to be inspected, the flap 29 is lifted tearing the tag 26 on the line of perforations 27 to free the said flap. A perforation 30, as shown best in Fig. 6 of the drawings, is formed in the flap 105 where the tag 26 previously existed. It will be noted, however, that the tag 28, tack 26, and body portion 17 of the envelop are held beneath the head of the tack 28. 100 105

After withdrawing the contents of the en- 110

velop when thus attached to a parcel, the same are returned to the envelop and the flap 29 is tucked under the free edge of the back 20 of the envelop.

5 The modified form of the invention shown in Fig. 3 provides an extra reinforcing patch 31 which is adhered to the back and body of the envelop adjacent the folded edge thereof. After the envelop back portion 20 has 10 been folded over on the body portion 17, the patch 31 is punched to form alined perforations 32. When, now, the envelop is closed, the retaining cord is threaded through the perforations 32, 23, 24 and 25, then tied, 15 and, if necessary, the ends thereof are sealed.

Claims.

1. An envelop comprising a body, flap and back of equal width and integrally connected, the raw edge of said flap being complementary to the raw edge of said back for facilitating the severing of said envelop from a continuous web; a reinforcing patch permanently attached to said flap and adjacent portion of said body for extending across the line of fold of said flap on said body, said patch and the flap and body superposed thereon having perforations formed therethrough, said perforations being disposed for alining when said flap is folded over said body; and a patch permanently attached to said back adjacent the raw edge thereof, said patches having raw edges corresponding with the raw edges of 5 said flap and said back.

2. An envelop comprising a body, flap and back of equal width and integrally connected, the raw edge of said flap being complementary to the raw edge of said back for facilitating the severing of said envelop from a continuous web; a reinforcing patch permanently attached to said flap and adjacent portion of said body for extending across the line of fold of said flap on said body, said patch and the flap and body superposed thereon having perforations formed therethrough, said perforations being disposed for alining when said flap is folded over said body; and a patch permanently attached to said back adjacent the raw edges thereof, said patches having raw edges corresponding with the raw edges of said flap and said back, said raw edges being coincidently formed by the single operation of a device employed for separating

the material forming successive envelops from a continuous web, said second-mentioned patch being perforated in correspondence with to aline with the perforations in the first-mentioned patch.

3. An envelop comprising an end-opening body having a folding flap, a reinforcing patch permanently adhered to said flap and the adjacent portion of the body of said envelop, said patch extending across the line 65 of fold of said flap; a second patch permanently attached to said envelop and to the inner surface thereof, said patch extending across the line of fold forming the bottom of said envelop and extending from the said 70 line of fold; and means for closing said envelop, said means embodying a plurality of perforations formed in said patches, said perforations alining to form continuous passages through the body portions of said envelop and patches.

4. An envelop embodying a back portion, a body portion, and a flap integrally attached to said body portion and adapted to be folded over said back portion in lapped 80 relation thereto for closing said envelop; a plurality of reinforcing patches, one rigidly attached to said body portion and flap, the other rigidly attached to said back portion, the exposed edges of said flap and said body 85 portion and of the patches attached thereto, respectively, being complementary in shape as permitting the formation thereof without loss of material when the envelop blank is cut from an elongated strip.

5. An envelop embodying a back portion, a body portion, and flap integrally attached to said body portion and adapted to be folded over said back portion in lapped relation thereto for closing said envelop; a plurality of reinforcing patches, one rigidly attached to said body portion and flap, the other rigidly attached to said back portion, the exposed edges of said flap and said body 95 portion and of the patches attached thereto, respectively, being complementary in shape as permitting the formation thereof without loss of material when the envelop blank is cut from an elongated strip, said body portion, flap and back portion being provided with perforations, said perforations 100 alining when said flap is in position to close said envelop.

CHARLES P. KLEEBAUER.
